(57) **CLAIM**

The ornamental design for a lens assembly, as shown and described.

DESCRIPTION

FIG. 1 is a front perspective view of a lens assembly;

FIG. 2 is front view thereof; and,

FIG. 3 is a back view thereof.

The broken lines illustrate portions of the lens assembly that form no part of the claimed design.

1 Claim, 3 Drawing Sheets

FIG. 1

FIG. 2

FIG. 3
